UNITED STATES PATENT OFFICE

152,590

DESIGN FOR A CARNIVAL WEIGHT-LIFTING
AMUSEMENT DEVICE OR THE LIKEPhillip Campbell, Whittier, and Edward George
Fox, Sr., Long Beach, Calif.

Application September 23, 1946, Serial No. 133,522

Term of patent 14 years

(Cl. D34—5)

To all whom it may concern:

Be it known that we, Phillip Campbell and Edward George Fox, Sr., citizens of the United States and residents of the cities of Whittier and Long Beach, respectively, in the county of Los Angeles and State of California, have invented a new, original, and ornamental Design for a Carnival Weight-Lifting Amusement Device or the like, of which the following is a specification, reference being had to the accompanying drawings, forming a part thereof.

Fig. 1 is a perspective view of the carnival weight-lifting amusement device or the like, showing our new design, and Fig. 2 is a plan view of the carnival weight-lifting amusement device or the like.

We claim:

The ornamental design for a carnival weight-lifting amusement device or the like, as shown.

PHILLIP CAMPBELL.

EDWARD GEORGE FOX, SR.
